UNITED STATES PATENT OFFICE

2,523,905

QUICK DETACHABLE LATCHING
ELECTRICAL CONNECTORJames S. Hellen, Locust Valley, N. Y., assignor to
Specialties, Inc., Syosset, N. Y.

Application January 29, 1949, Serial No. 73,576

3 Claims. (Cl. 173—328)

1

This invention relates to electrical connectors of the type having a plurality of pins on the header or plug section and a plurality of sockets on the socket section adapted to receive said pins in order to establish electrical connection from a component or unit connected with said pins and a source of electric energy.

Under some conditions it is desirable to lock the header and socket sections together when in fully engaged position with some means for providing a ready unlocking of the sections to permit disconnecting the connector. Heretofore locking means have been provided of various forms but in the aviation industry broadly and the field of electrical control systems for aircraft especially, as well as in other related fields, such proposals have resulted in heavy and bulky connectors. Decrease both in weight and in bulk are necessary with respect to connectors of this type, for such uses.

Furthermore, a positive and rapid locking and easy, rapid disconnect or unlocking are highly desirable features for such connectors, particularly bearing in mind that a large number of connectors may be used in a single airplane or other similar installation.

Accordingly, it is a principle object of the present invention to provide a novel and improved electrical connector of the type described having a positive and rapid locking action and a rapid, easy unlocking or disconnecting action.

In such connectors it is also desirable to have means to hold the wires within the body thereof tightly but without injury thereto, so that any pull on the wires will not be transmitted to the ends thereof which are soldered or otherwise conductively attached to the lugs or terminals communicating with the sockets.

It is accordingly a further principle object of the present invention to provide, in a connector of the type referred to, new and useful means for securely holding the wires leading from the socket terminals within the body of the connector without subjecting them to damage such as by bruising.

A further object of the invention is to provide a new and useful connector of the type referred, having a positive locking action and rapid, easy connecting and disconnecting, within a minimum of space to suit the particular requirements of the aviation and kindred industries.

Other objects and advantages of the invention will be obvious and apparent during the course of the following description.

In the accompanying drawings, forming a part

2

of this application, there is illustrated one embodiment of the present invention.

Of the drawings:

Figure 1 is an elevation, on an enlarged scale, and with the left half thereof with parts in section, of a new and useful connector according to the present invention;

Figure 2 is a composite breakdown elevation showing all the parts of the connector of Figure 1, with some parts in section, in relative position for assembly;

Figures 3 and 4 are details of the locking mechanism shown in the sectioned half of Figure 1, Figure 3 showing the locked position and Figure 4 showing the unlocked position;

Figure 5 is an elevation, on an enlarged scale, of the connector body unlocking ring and nut body forming the socket-containing part of the connector of Figure 1, in assembled position and ready to be attached to the pin header-containing part of the connector;

Figure 6 is a plan view of the connector body of the connector of Figure 1;

Figure 7 is a section of the connector body of Figure 6 on the lines 7—7 of Figure 6;

Figure 8 is a plan view of the unlocking ring of the connector of Figure 1;

Figure 9 is a section of the unlocking ring of Figure 8 taken on the lines 9—9 of Figure 8;

Figure 10 is a bottom view of the cap of the connector of Figure 1; and

Figure 11 is a section of the cap of Figure 10 taken on the lines 11—11 of Figure 10.

Generally, in practicing this invention there is provided a connector having two essential parts, the one carrying a conventional multi-socket unit and the other a conventional multi-pin header unit.

The multi-socket unit is mounted within a connector body which in turn carries an unlocking ring thereabouts. The various wires are soldered or otherwise attached to the terminals communicating with the sockets and are led through an exit port in this part of the connector between

45 resilient cushions formed by a washer of rubber or the like in the lower end of the connector body and a shaped plug of rubber or the like located to be within the area formed by the wires, a suitable screw nut and ferrule forcing the washer and plug toward each other to trap the wires therebetween and grip them firmly.

The ferrule may be so shaped, if desired, as to have an interior portion of complementary shape 50 to the end of the plug, so that the wires may also

be gripped between the shaped part of the ferrule and a part of the plug.

At the end opposite the ferrule, the unlocking ring is formed with one or more legs with spaces or slots therebetween. The other part of the connector comprises a cap carrying the multi-pin header unit, as well as the lid of a can or other container if the component to be connected to the pins is to be contained therein, for instance, for hermetically sealing-in the component. The cap is arranged with interiorly projecting spring elements or fingers which can be forced outwardly against their spring bias when desired.

To this end, the connector body carries at its end an annular flange of greater diameter than the body itself over which these spring elements can be sprung until they fall beneath the flange to hold the cap in place, each spring finger lying within one of said spaces or slots in the unlocking ring, there being preferably as many spring elements or fingers as slots provided in the ring.

By rotating the unlocking ring on the connector body, the solid portions or legs force the spring fingers back beyond the flange, to permit disengagement of the cap and body.

Preferably, the unlocking ring is spring biased with respect to the connector body so that these two parts will assume the same position at all times except when the ring is rotated for unlocking the device.

Suitable polarizing means are preferably provided, comprising a shaped notch in the cap and a cooperating lug on the connector body.

Thus, the connector according to the present invention comprises in its essential elements a body for housing a socket unit having a flange at one end, a cap for housing a cooperating pin unit, internal spring fingers on the cap which can be sprung over the flange and beneath the shoulder formed thereby to lock the cap on the body simply and rapidly, and an unlocking ring rotatable on the body, having slotted sections in which the fingers can normally be located when in locked position and legs which act when the ring is rotated to cam the fingers against their spring bias out of the way of the flange, to permit a disengagement of the cap and the body in an easy and rapid manner.

Referring now especially to the accompanying drawings wherein for the purpose of illustration is shown a preferred embodiment of the present invention, in Figures 1 and 2, a connector according to the present invention is shown incorporating a conventional multiple-pin terminal header 20 and a conventional multiple-socket unit 21 to be associated therewith in usual manner. The terminals 22 of header 20 are adapted to be connected as desired to any electrical component or unit which will normally be housed within a casing or box 23. Pins 24 of header 20 which communicate with terminals 22 depend downwardly and are adapted to enter sockets 25 of unit 21 when all the parts of the connector according to this invention are in the locked position, as in Figure 1.

It is obvious that any number of pins 24 and cooperating sockets 25 may be provided for any desired purpose of connecting a component in box 23 to an outside source of electrical energy. Sockets 25 communicate with lugs 26 which are adapted to be connected wires 27, as by soldering as at 28.

Conventionally, from socket unit 21 there depends a centering pin 29, and in accordance with one feature of the present invention said pin is

caused to support a plug member 30 having a frustro-conical nose portion 31, this nose 31 at least, being formed of a soft yielding material, such as rubber, the support being made possible by virtue of a blind bore 32 in that end of plug 30 away from said nose 31.

As will be seen particularly from Figures 1 and 7, socket unit 21 may be housed within the interior of main connector body 33, being seated against shoulder 34 formed therewithin. A pin 35 protrudes through the body 33 and is held therein in any desired manner, the function of the protruding end being hereinafter brought out. The head 36 of the pin acts as a polarizing means for orientating socket unit 21 in the interior of body 33 by cooperation with a cut-out 37 in a flange portion 38 of socket unit 21. A spacer 39 formed as a hollow cylinder of suitable material such as a hard thermoplastic embraces socket unit 21 and extends into contact with the under face of flange 38 (Figure 1). Connector body 33 has an external lower screw-threaded section 40 with which may be engaged an interiorly threaded securing nut body 41 having a body portion 42, interior thread 43 and orifice 44, said body being knurled exteriorly as at 45 for greater grip thereupon.

A hollow ferrule 45 having an annular flange 46 is adapted to be carried by body portion 42 into contact with a resilient washer 47 formed of suitable resilient material such as soft rubber, said washer bearing against the lower end of spacer 39. Thus, by assembling the parts comprising connector body 33, socket unit 21, plug 35, spacer 39, washer 47, ferrule 45 and nut body 41 into the positions shown in Figure 1, ferrule 45 will cause a plurality of the wires 27 surrounding the plug 30, and preferably grouped together in a sleeve 48 of any desired material, to be resiliently but firmly held by virtue of the yielding property of washer 47 and nose 31. Washer 47 will be distorted as at 49 to assist this grip if the diameter of the washer is made slightly oversize relative to the portion of the interior of body 33 in which it is seated, this being preferable according to the present invention. Furthermore, if desired, the grip upon the wires may be additionally enhanced by shaping the interior face of a portion at least of ferrule 45 to be complementary to and a mate of, the corresponding portion of the frustro-conical nose 31, this shaped portion being shown at 50 in Figure 2.

Accordingly, one object of the present invention has been achieved by this structure by providing a positive grip on the plurality of wires within sleeve 48 which will not give way under extreme conditions of pulling on the wires 27 and yet will not bruise or otherwise injure the wires, due to the resiliency of the washer 45 and nose 31.

According to a further feature of the present invention, there are provided means for quickly but positively connecting and disconnecting socket unit 21 and header 20. To this end, an unlocking ring 55 is provided, formed as a hollow cylinder which may be placed over body 33 to surround same and be rotatably mounted thereon as shown in Figures 1 and 5. Ring 55 has a thick walled body portion 56 which is provided with an external knurled surface 57 to permit easy gripping. A thinner walled section 58 is integral with body portion 56 and is slotted as at 59, four slots being specifically and exemplarily shown, as in Figure 8, in the embodiment.

ment being described. The solid portions remaining form legs 60 and extend upwardly as shown in Figure 2 substantially into contact with an annular flange 61 formed on the upper face of connector body 33. Legs 60 terminate in inwardly projecting feet 62 which are of such dimension that the diameter of a circle generated by the inner faces thereof is only slightly larger than the external diameter of connector body 33 at the plane of association. Thereby, the feet 62 act substantially as guides for rotary movements of unlocking ring 55 on connector body 33, the annular space between the external face of the connector body and the interior face of the ring being still preserved in a major portion of their respective lengths. In this space a spring 63 is inserted in order to assert a resilient action between ring 55 and body 33. Spring 63 is attached at one end to pin 35 by a loop 64, which pin also limits rotary movement of the ring in either direction since it projects into one of the slots 59 and contacts either one or the other of sides 65A, 65B of the specific slot in which it lies (Figure 5). The other end of spring 63 is bent back and hooked over the side of another slot as shown at 66. The contour of spring 63 is shown in Figure 2 in its relaxed position and partially in dotted lines in Figure 5 where it is shown in position on pin 35 and hooked over at 66, it being born in mind that the longitudinal plane through the spring element will be curved to suit the contour of the segment of the surface of body 33 over which the spring lies. Thus, in the assembled position shown in Figure 5, ring 55 has rotation counter-clockwise on connector body 33 against action of spring 63, which rotation is limited by contact of pin 35 with the right hand face 65B and upon release of the turning action, the parts will return to the position of Figure 5 under urge of spring 63 and contact of pin 35 on the left hand face 65A.

It will be obvious from the description hereinbefore given, and particularly from Figures 5, 8 and 9, that any yielding object lying in the circumferential plane of legs 60 and located in any slot 59 in the position of the parts in Figure 5 will be urged out of said plane by cam action when said ring 55 is rotated on body 33 by contact of the sides of the slot, and this principle is relied upon in the present invention. To this end, a cap 67 is provided (Figures 10 and 11) formed as a cylindrical member of an interior diameter large enough to normally fit snugly but slidingly over annular flange 61 on connector body 33. In the wall of cap 67 are formed a plurality of inverted L-shaped cut-outs 68, these being of number and spacing apart equivalent to the slots 59 in ring 55. The material forming cap 67 is chosen of sufficient resiliency that when the shaped portions or tongues 69 are upset inwardly they provide upsets or spring fingers 70 of sufficient resiliency that they will give when cammed outwardly back into the circumferential plane of the wall of the cap by means of legs 60, as hereinafter explained. Since cap 67 is a snug but sliding fit on flange 61 of body 33, the cap and body can be readily engaged by simply pushing the parts together, the fingers 70 yielding sufficiently to permit such engagement and, as soon as the fingers 70 are below the lower face of flange 61 and under the shoulder formed thereby, they snap thereunder by their own resiliency so that the cap is secured

in place. This is clearly shown in Figure 1 and in the detail of Figure 3. To disconnect the connector, all that is necessary to do is to rotate the ring 55, when the legs 60 will contact the spring fingers 70 urging them back again toward the initial position they occupied in the circumferential plane of the wall of the cap before being forced out or upset in which position the cap and body can obviously be disengaged.

This camming action is clearly shown in the detail of Figure 4. With the cap and body disengaged, the spring 63 will return ring 55 and body 33 to initial position as in Figure 5.

Within the cap 67 there is preferably fitted a sealing washer 71 of soft rubber or like resilient material and to further add to the sealing of the interior of the body of the whole connector when in locked position, the upper face of connector body 33 carries an annular ridge 72 which deforms the rubber washer 71, as clearly shown in Figure 1.

It is obvious that it is necessary for the cap and body to be engaged with the four spring fingers located within the four slots, and in order to make this certain, as well as to polarize the sockets and pins of the connector, a polarizing lug 73 is formed as part of flange 61 and a co-operating polarizing slot 74 is formed in the wall of cap 67.

Header 20 is permanently associated with cap 67 by soldering a flange 75 on the header and an annular protuberance 76 on cap 67 to a lip 77 on the lid 78 which fits on the case 23 containing the component, the solder being flowed into the annular recess 79 formed by these three parts (see Figure 1).

The assembly of the parts to form the complete connector is a simple matter as will be seen from Figure 2 and, if desired, a retainer ring (not shown) may be used to hold ring 55 and connector body 33 together during assembly rather than rely upon spring 63 to perform this function.

In order to further assist the camming action of legs 60, the entering edges of the legs relative to the fingers 70 may be chamfered or otherwise shaped, as at 80, to give an entering wedge effect upon the fingers, whereby the operation of unlocking will be smoother with less wear on the fingers.

It is obvious that instead of forming spring fingers 70 as above shown, if desired, separate spring members equivalent to 70 could be soldered or otherwise fastened inside ring 55 so as to be yieldingly protruding into the interior of the ring in position to be cammed into suitable cut-outs equivalent to cut-outs 68 when acted upon by legs 60. Alternatively, no cut-outs will be needed in such a construction if the cap 67 is made of sufficiently large internal diameter relative to the diameter of flange 61 to accommodate the spring fingers 70 in the space therebetween.

In the description hereinbefore given, reference has been made to the engagement of the cap and body portions without qualifying which of these portions is forced into engagement with the other.

In the specific embodiment using a multi-pin header, the component will be placed in case 23 which will thereafter be hermetically sealed with the cap 67 mounted thereon. Case 23 will then be anchored and thus the body assembly as shown in Figure 5 will be pushed into the cap to effect 75 the rapid and easy connection desired.

It is obvious, however, that for other uses than the specified use given above, the cap could be the part of the connector to be forced upon the body assembly or both parts could be unanchored and pressed into locking engagement to form a multi-wire line connector.

It is to be understood that the form of my invention, herein shown and described, is to be taken as a preferred example of the same, and that various changes in the shape, size and arrangement of parts may be resorted to, without departing from the spirit of my invention, or the scope of the appended claims.

Having thus described my invention, I claim:

1. An electrical connector of the type referred to comprising in combination a body adapted to interiorly house a socket unit, said body having an annular flange at one end; a cap adapted to house interiorly a pin unit complementary to said socket unit, said cap being of interior diameter sufficiently larger than the diameter of said flange to loosely fit thereover; a plurality of resilient fingers projecting interiorly of said cap in such a position as to be pressed outwardly by said flange when said cap is forced into engagement with said body until said fingers can spring under the shoulder formed by said flange, to hold said cap in locked position on said body; an unlocking ring mounted for rotation on said body; and a plurality of legs projecting from said ring into the interior of said cap when in locked position with said fingers lying in the spaces formed between said legs, said legs lying in such a diameter relative to the diameter of said flange that upon rotation of said ring on said body, said fingers will be cammed outwardly against their resiliency to a position to permit them to clear said flange and allow disconnection of said cap and said body.

2. An electrical connector of the type referred to comprising in combination a cylindrical body having an annular flange at one end forming a shoulder therebeneath, and a threaded section at the other end; a multi-socket unit housed within said body; a cylindrical cap of internal diameter larger than the external diameter of said flange; a multi-pin unit complementary to said multi-socket unit housed within said cap; a plurality of resilient fingers within said cap, projecting inwardly into the normal path of entry of said flange within said cap and displaceable outwardly by said flange and beyond said path of entry by action of pressing said cap and said body into contact whereafter said fingers spring into locking position beneath said shoulder formed by said flange; a plurality of legs on one end of said ring formed by slotting the ring at that end, the number of slots so formed equalling the number of fingers interiorly of said cap, said legs projecting into said cap when the connector is in locked position with said fingers lying within the slots and circumferentially embraced by the sides of said legs; resilient means comprising a spring attached between said body and said ring for applying a spring return to rotatory movements

of said ring on said body in one direction; a pin projecting outwardly from said body and arranged to lie within one of said slots to act as a limit of such rotatory movements by abutting against one or the other side of the slot in which it lies, said pin also serving to anchor one end of said spring to said body, the other end being attached to said ring by bending a portion of the spring over a side of another slot, the spring being then carried in a space between the exterior of the body and the interior of the ring; and a nut having an interior thread complementary to the thread on said body; whereby the cap and body may be readily disconnected by rotating the ring on the body to cause the legs to cam the fingers beyond the flange and readily connected by pressing said cap and body into contact with said cap over said flange.

3. An electrical connector of the type referred to comprising in combination a cylindrical body having an annular flange at one end forming a shoulder therebeneath, and a threaded section at the other end; a multi-socket unit housed within said body; a cylindrical cap of internal diameter larger than the external diameter of said flange; a multi-pin unit complementary to said multi-socket unit housed within said cap; a plurality of resilient fingers within said cap, projecting inwardly into the normal path of entry of said flange within said cap and displaceable outwardly by said flange and beyond said path of entry by action of pressing said body into said cap whereafter said fingers spring into locking position beneath said shoulder formed by said flange; a cylindrical unlocking ring surrounding said body; a plurality of legs on one end of said ring formed by slotting the ring at that end, said legs projecting into said cap when the connector is in locked position with said fingers lying within the slots and circumferentially embraced by the sides of said legs; resilient means for applying a spring return to rotatory movements of said ring on said body in one direction; a pin projecting outwardly from said body and arranged to lie within one of said slots to act as a limit of such rotatory movements by abutting against one or the other side of the slot in which it lies; and a nut having an interior thread complementary to the thread on said body; whereby the cap and body may be readily disconnected by rotating the ring on the body to cause the legs to cam the fingers beyond the flange.
